GRINDING MACHINE

Merton H. Arms and Paul A. Grobey, Springfield, Vt., assignors to Bryant Chucking Grinder Company, Springfield, Vt., a corporation of Vermont

Application January 9, 1947, Serial No. 721,052

22 Claims. (Cl. 51—50)

1

This invention relates to grinding machines and the like.

One object of the invention is to provide improved mounting of the work and tool carriages by which accurate control and alinement of these parts is readily obtained and which is relatively insensitive to temperature changes and variations in temperature between various machine parts.

A further object is to provide improved mountings and controls by which accessibility of the work for inspection or replacement is facilitated without requiring an extended motion of the parts to sufficiently separate the work and grinding wheel.

Still another object of the invention is to provide for automatic adjustment of the limits of traverse as the end face of a grinding wheel employed for face grinding is progressively removed by wear and truing.

Still another object is to provide an interlock between face grinding stop mechanism and the power traverse mechanism so that only one of these may be in operation at one time.

A further object is to provide traversing mechanism for the traversing carriage by which a nearly constant velocity throughout the traversing stroke may be obtained, which is particularly desirable when grinding long holes, or a harmonic motion at high speed which is in some cases desirable when grinding short holes.

Still another object is to provide a rigid support for the carriages when they are in grinding positions.

Further objects and advantages will appear from a description of an embodiment of the invention shown in the accompanying drawings in which

Figures 1 and 2 are right end and front elevations, respectively, of a grinding machine embodying the invention.

Figure 3 is a sectional view on line 3—3 of Figure 2.

Figure 3a is a detail sectional view through the interlock valve in face grinding angular position.

Figure 3b is a detail sectional view on line 3b—3b of Figure 3a.

Figures 4 to 7, inclusive, are detail sectional views on the correspondingly numbered sections of Figure 3.

Figure 8 is a detail sectional view on line 8—8 of Figure 6.

Figure 9 is a fragmentary view partly in side elevation and partly in central section through a wheel truing device.

Figure 10 is a fragmentary view partly in horizontal section through the work carriage moving mechanism.

Figure 11 is a detail sectional view on line 11—11 of Figure 10.

2

Figure 12 is a detail sectional view on line 12—12 of Figures 1 and 11.

Figure 13 is a detail vertical sectional view on line 13—13 of Figure 3.

Figure 14 is a view similar to Figure 13, but showing the work slide in facing position.

Figure 15 is a detail sectional view on line 15—15 of Figure 13.

Figure 16 is a fragmentary view to a larger scale similar to a portion of Figure 2 and showing the wheel carriage traverse mechanism.

Figure 16a is a view similar to a portion of Figure 16, but with parts shown in different positions.

Figure 17 is a detail sectional view on line 17—17 of Figure 16.

Figure 18 is a detail sectional view on line 18—18 of Figure 17.

Figure 19 is a velocity space diagram illustrating the motion of the traversing carriage when the universal joint is set for straight line drive and where it is set for an angular drive at 45°.

As shown best in Figures 1 and 2, this machine includes a bed 1 on which is mounted a pair of carriages 2 and 3, the carriage 2 being arranged to support a work spindle carrying a work supporting chuck 5 for a work piece 6, and the carriage 3 being a tool carriage and as shown supporting a grinding wheel spindle 7 which carries 30 on its projecting end a grinding wheel 8.

Carriage mounting

One portion of the invention relates to the mounting of the two carriages 2 and 3. Each is supported on a pair of cylindrical guide bars 10 and 11 for the work carriage and 12 and 13 for the tool carriage. One of each of these guide bars is rigidly carried by the bed 1, the guide bar 10 for the work carriage and the guide bar 12 for the wheel carriage being so shown. The guide bars 11 and 13 are supported from a pair of carrier bars 14 and 15, respectively. Each of these carrier bars is supported at opposite ends on vertically adjustable jack screws 16 (see Figure 6 for carrier bar 13 support), and may be secured in vertically adjusted position as by screws 17 passing through vertical slots in the respective carrier bars and threaded into the bed 1. By this means the carrier bars may be adjusted vertically and independently at each end.

These carrier bars are arranged to support at spaced points, reeds 18 which are rigidly secured at their upper ends to the guide bars 11 or 13. The carrier bars engage with vertical faces 19 on the bed 1 and the planes of flexure of the reeds are perpendicular to the planes of the guide bars of the corresponding set, each set comprising a pair of guide bars 10, 11, and 12, 13. The reeds as shown are in the planes of the central axes of the respective bars which avoids any rolling effect of the bars as the reeds flex.

The carriages 2 and 3 are supported on the guide bars 10 and 11 and 12 and 13, respectively, on three sets of preloaded ball bearings, two sets of these bearings engaging one of the guide bars at spaced points therealong, and the other single set engaging the other guide bar of the pair. As shown, for example, two of these ball bearings at 20 and 21 are engaged with the fixed guide bar 10 and a single such ball bearing engages the bar 11. Similarly for the wheel slide, two spaced sets of such bearings are mounted on the bar 12, while a single set of such bearings is mounted on the bar 13. By this mounting the carriages may be moved freely along the guide bars in rectilinear paths and with maximum smoothness. The guide bars 10 and 12 which are provided with the pairs of spaced ball bearings are each provided with one support from the bed 1 located between these bearings as at 10a and 12a and a support 10b and 12b outwardly of one of these bearings. When the two carriages 2 and 3 are in grinding position, the ball bearings for each are close to these supports of both bars, thus giving the most rigid support to the carriages for the grinding operation, and avoiding flexure of the supporting bars which might otherwise occur. By reason of the reed mounting of one of the guide bars for each carriage and the independent vertical adjustment of each end of this guide bar transverse to the general plane of these guide bars, the guide bars of each pair may be adjusted into exact coplaner relation, and any variations due to temperature changes or to unequal temperature changes of various portions of the machine are taken up automatically by the flexing of the reeds. This mounting arrangement makes it easy to adjust the planes of motion of the two carriages in the desired precise relationships and to so maintain them during operations of the machine, and despite warping changes which may occur through seasoning of the bed and through temperature changes and variations of temperatures of different portions of the bed 1. In order to protect the bearings on the guide bars from access by foreign materials, these bars may be surrounded by flexing bellows 25 which seal off these guide bars from their ends to the guided portions of the respective carriages.

The mounting of the carriages as thus described is not claimed per se herein but forms subject matter of a divisional application Serial No. 787,448, filed November 21, 1947, for Carriage Mounting.

Means are provided by which the wheel carriage can be reciprocated. To this end the wheel carriage 3 has depending therefrom a lug 30 (see Figure 2) which may be connected through a link 31 to a lug 32 extending laterally from a wide arm 33. This arm 33 is secured at its lower end to a rock shaft 34 journaled in the lower portion of the machine base. The upper end of the arm 33 has an extension 35 provided at its upper end with a handle 36 by the rocking of which the rock arm 33 is rocked, causing a traverse motion to be imparted to the slide 3.

Work carriage moving mechanism

In order to facilitate access to the work piece when the wheel 8 is retracted and without requiring a long travel of the carriage 3, provision is made in accordance with this invention, for moving the work carriage laterally of the travel of the carriage 3 and as shown, forwardly, so that the work is brought out of its normal position

where the grinding wheel may operate upon the work and freely accessible to the operator. To this end, means are provided by which when the wheel carriage has been moved to retract the wheel from the work to a predetermined extent clear of the work, the work head with its carriage is automatically moved forwardly. This means, as shown in Figure 10, may comprise a fluid actuated vane motor 40. As shown in Figure 10, this motor comprises a cylinder within which is rockably mounted a vane 41 fixed to a shaft 42 coaxial with the motor 40. This vane may be moved angularly throughout substantially 180° by fluid under pressure, such as compressed air or hydraulic fluid, which may be delivered into the motor 40 through either of a pair of ports 43 and 44, the port not being employed at any time for the supply of driving fluid being the discharge port. This vane motor is shown as attached to the work carriage 2. The shaft 43 carries a crank 45 at its lower end, as shown best in Figures 1, 10 and 11, and this crank carries a connecting rod 46 pivoted between a pair of ears 47 projecting backwardly from the rear end of an axially movable non-rotatable feed screw 48 (Figure 13) on which is threaded a rotary feed sleeve 49 journaled in the machine frame and arranged to be turned by rotation of a feed shaft 499 connected thereto through intermeshing gears 491 and 492.

Assuming the parts to be in the full line position of Figures 3, 10, and 11, the carriage 2 then being in its back position with a stop abutment 493 thereon engaging the forward end 35 of the feed screw 48 as shown in Figure 13 and held thereby by a counterweight 494 (Figure 1) connected to the carriage 2 through a cable 495, fluid under pressure delivered to the motor 40 through the pipe 46 will act to rotate the crank arm 45 backwardly in a counter-clockwise direction as viewed in Figure 10, this acting to move the carriage 2 forwardly of its normal working position, the carriage and the motor then taking the dotted line position shown in Figure 10 and with the stop abutment 493 spaced forwardly of the feed screw but to a greater distance than shown in Figure 14. The action of the crank is to move the carriage 2 quickly from one to the other position with a slow motion at the ends of its stroke adjacent to its dead center positions, which is of particular importance, particularly when the abutment 493 approaches the feed screw, and by attaching the link 46 to the feed screw, the same easy approach is provided regardless of the setting of the feed screw for different diameters.

Means for so actuating the vane motor to produce the desired movements of the work carriage when the wheel is retracted or about to be moved into operative position, is shown in Figure 3. The carriage 3 at its rear end is provided with a bracket 50 from which projects an adjustable stop screw 51. When the carriage 3 reaches a predetermined retracted position, this stop 51 engages the forward end of a valve stem 52 of a controlling valve 53. In the position shown in Figure 3 where the carriage 2 is in its rearward operative position, and the wheel carriage 3 is in its working position, the stop 51 is out of contact with the valve stem 52, so that the spool valve 54 is in the position shown, being pressed to the left as by the spring 55. Fluid under pressure conducted to the valve 53 through the pressure pipe 56, then passes around the valve 54 and through the pipe 44 and past a

valve 154, which will be described later, into the vane motor 40, while the pipe 43 is discharging fluid from the opposite side of the vane around the valve 54 through the discharge pipe 51. When the feed carriage is moved to the right to retract the wheel from the work to an extent sufficient for the stop 51 to engage the stem 52 and press the valve 54 to its rearward position, the pressure pipe 56 is placed in communication with the pipe 43 leading to the vane motor, and the pipe 44 is brought into communication with the exhaust pipe 58, so that immediately the vane motor is turned from the position shown in Figure 3 in a direction to move the work carriage forwardly into the dotted line position of Figure 10. As soon as the wheel carriage is moved to the left to bring the wheel into operative relation to the work to an extent sufficient to release the pressure from the stop 51 on the stem 52, which is well before the wheel reaches the end of the work, the valve 54 is immediately moved by the spring 55 to its left hand position shown in Figure 3, which changes the valve setting so as to move the vane motor in a direction to return the work carriage to its rearward operative position.

Power traverse mechanism

While the wheel carriage may be moved by hand if desired, means are also provided by which it may be given its traversing motion by power, and in order to avoid contact of the wheel with the work adjacent to the end portions of its stroke for a substantially greater length of time than at its center of motion, which is important where the stroke is of substantial length, means may be provided by which the traverse may be adjusted so as not to take place in harmonic motion, but is speeded up somewhat away from the center of stroke and retarded at the center. By this means bell mouthing of the work is avoided. For short strokes harmonic motion is desirable.

The power means, as shown in Figures 2, 5, and 13, comprises an arm 60 fulcrumed at the lower portion of the machine base at 61 and at its upper end adapted to be operatively connected to the carriage 3. As shown best in Figure 5, this operative connection comprises a latch 62 fulcrumed at 63 to a cross pin carried by the carriage 3 by means later to be described, and having at its rear end a hook 65 adapted to engage a cross pin 66 bridging a slot 67 in the upper end of the arm 60. When the latch 62 is in the full line position shown in Figure 5, the arm 60 is operatively connected to the carriage 3. Intermediate its length, the arm 60 is connected to a connecting rod 70 (Figures 2, 16 and 17) which engages a crank pin 71 on a crank arm 72. This crank pin is adjustable for throw on the arm 72 and is therefore formed as a flanged sleeve carried by a T bolt 73 (see Figures 16, 17 and 18) adjustable diametrically lengthwise of the arm 72. For effecting such adjustment, the arm 72 has journaled therein a threaded rod 74 provided with a hand wheel 75 at its outer end, this threaded rod being threaded through the T bolt 73. The link 70 is made adjustable in length in order to change the limiting end positions of the path of motion of the wheel carriage 3, and to this end the link 70 comprises telescopically related sections 80 and 81 which may be clamped in adjusted relation by means of a serrated clamp bar 82 engaging mating serrations in the section 81

and held in position as by a bolt and nut at 83. The arm 72 may be provided with a scale 76 for cooperation with a pointer 84 carried by the link section 80 when the link 70 comprising the sections 80 and 81 is in the dead center relationship to the arm 72 shown in Figure 16a, in which position an arrow 85 on a guard plate 86 carried by the arm 72 is opposite to an arrow 87 or an element 88 of a bearing bracket 89 carried by the machine frame.

The arm 72 has an integral shaft portion 90 which extends through a bearing 91 in the bracket 89. Inwardly of this bracket 89, this shaft portion 90 has a fork 94 bridged by a pivot 95. This pivot 95 passes through a block 96 carried by a transverse pivot 97 journaled between the arms of a fork 98 carried by a shaft 99, the two forks, the pivots, and the block constituting a single universal joint of the well known Hooke's type. The shaft 99 is journaled in a bearing 100 mounted in a bracket 101 supported eccentrically on a table 102 clamped to the machine frame bracket 89 by a bolt 103 in a clearance hole in the table. The table 102 has pivoted thereto beneath a portion of the bracket 89, a platform 105 from which a motor 106 is suspended. This motor is connected through a belt 107 with a belt pulley 108 fixed to a worm shaft 110 which is journaled in the bracket 101 and which meshes with a worm wheel 111 carried by a hub portion 112 which is secured to the fork 98. The free end of the platform 105 which supports the motor has threaded connection through a nut 114 with an adjusting bolt 115 by the adjustment of which the proportion of the weight of the motor effective to tension the belt 107 may be adjusted as desired. It will be seen that by rotation of the motor 106, the worm 110 will be driven, imparting rotation to the worm wheel 111 and the fork member 98 of the universal joint and through this, motion will be transmitted to the shaft 99 and the crank pin 71 by which oscillation of the wheel carriage actuating arm 60 will be produced. When the shafts 99 and 90 are in axial alignment, the shaft 99 will be driven from the shaft 90 in uniform angular velocity, the shaft 99 being so driven from the motor 106. However, by adjusting the table 102 angularly about the axis of the pivot 97, the shaft 99 is brought out of alignment with the shaft 90, whereupon the shaft 99 will be driven at a variable angular velocity from the shaft 90 and the maximum extent of this variation will take place when the shaft 99 is arranged at 45° out of alignment with the shaft 90.

When the shafts 99 and 90 are arranged in axial alignment, the motion imparted to the wheel slide will be substantially harmonic as shown by the curve *a* of Figure 19, and as is well known, harmonic motion of a reciprocating wheel carriage produces a relatively rapid motion in the center of the path and relatively slow motions toward the ends of the path, which cause the wheel to remain in contact with the work a longer time toward the ends of the path than at the center. By adjusting the table 102 so that the shaft 99 is angularly displaced from alignment by 45°, the velocity space relation shown by the curve *b* (Figure 19) is produced. It will be noted that the velocity is substantially linear throughout the major portion of the traverse between the points *x* and *y*. Particularly where the stroke is of substantial length, this modification of the velocity of traverse to sub-

stantially a linear value is of substantial importance in grinding to close tolerances and it will be noted that this is produced without the use of elliptical gears or other complicated mechanisms which may result in an uneven or jerky motion of the carriage, and this arrangement makes possible any intermediate setting of the table to produce any desired intermediate velocity space diagram between harmonic motion, curve *a*, and the substantially straight line motion shown in curve *b* of Figure 16.

This power traverse mechanism is not claimed herein as it forms subject matter of a divisional application Serial No. 789,836, filed December 5, 1947, for Carriage Reciprocating Mechanism.

Facing mechanism and adjustments

It is also possible with this machine to employ the grinding wheel for facing the work, and this is done in an intermediate position of the work carriage between the operative position shown in full lines in Figures 3 and 10 and the dotted line position shown in Figure 10, at which time the outer end face of the grinding wheel is opposite to a portion of the end face of the work. Where such facing is desired, the casing of the vane motor 40 is provided with an extension 150 (see Figure 12) which is bored to receive a piston valve 151 having a pair of spaced cannelures 152 and 153. The inner end of this valve extends into a recess 154 in the top end wall 155 of the vane motor and into the path of motion of an arm 160 clamped to the shaft 42 of the vane motor, and carrying at its outer end a roller 161 positioned to impinge upon the inner end of the valve 152 when the vane in the vane motor 40 is substantially midway of its end positions, this retracting the valve 151 against the pressure of a spring 162 engaging the outer end. When the valve 151 is in its normally projected position, the cannelure 152 is interposed in the pipe 44 leading to one end portion of the vane motor, and a pipe connection 163 is closed off from a discharge pipe 154. Between the vane motor 40 and the valve 54, the pipe 44 is provided with a branch 168 leading to the forward portion of the machine into a valve casing 170 shown best in Figures 3a and 3b. This casing 170 has a rocking valve 171 therein, which, when the valve 171 is in position for internal grinding, positions a longitudinal passage 175 therein connecting the pipe 168 to a pipe 176 which joins the pipe 44. Thus when the wheel carriage is moved out of engagement with the valve 54 in the position shown in Figure 3, fluid pressure may pass the valve 54 not only directly into the left side of the vane through the pipe 44, but also through the branch pipe 168, the passage 175 of the valve 171, and the pipe 176 thereto.

When it is desired to face grind, however, the valve 171 is turned to bring a passage 178 therein into the position shown in Figure 3a where the pipe 176 is connected to the pipe 163 which leads back to the valve 151. As soon as the valve 151 is pushed rearwardly against the action of the spring 162 to bring the cannelure 153 in line with the pipes 163 and 164, the left hand side of the vane motor is opened through the pipe 176, the passage 178 of the valve 171, the pipe 163, cannelure 153 of the valve 151, and the pipe 164, to discharge. At the same time the right hand side of the vane is also opened to discharge through the pipe 43 and past the valve 54, so that both sides of the vane motor are now open to discharge and the motion of the vane motor stops.

At the same time that the valve 170 is thrown

into the angular position which causes the stopping of the vane motor in its intermediate angular position, it throws down a stop bar 180 held by a forked arm 181, between a pair of abutments 182 and 183 as shown in Figure 14. The abutment 182 comprises a hardened plug seated in a fixed frame member 185, while the abutment 183 is yieldingly carried by the outer end wall of the work carriage 2. As shown in Figure 13, this abutment 183 in its normal backward spring-pressed limit of motion is arranged for micrometric adjustment in the line of travel of the work carriage. To this end it is shown as supported in a recess in the outer end of a plug 190 into which is threaded the extremity of a screw 191. This screw 191 is provided with an enlarged diameter portion 192 which is threaded through a sleeve 194 clamped in the end wall of the carriage 2, one end of the sleeve 194 having an integral shoulder 195 and the other end having threaded thereon a locking collar 196. The outer end of the screw 191 is secured to a collar 198 by which it may be turned. The screw 191 may be a differential screw, its two threaded portions being of slightly different pitch so that a very fine adjustment of the axial position of the abutment 183 may be afforded. A graduated disk 200 carried by the screw and cooperating with an index element 201 fixed to the carriage 2 will indicate to the operator the adjusted position. A shouldered element 199 threaded on the plug 190 and engaging the valve 171 for alignment limits the spring pressed position of the abutment 183 with respect to the plug 190.

As the stop member 180 is moved into position between the abutments 182 and 183, it serves to accurately define the mid-position of the carriage 2 at which the carriage will stop when the valve 153 is moved to its rearward position. The work carriage then comes to rest in the mid-position suitable for face grinding, whereupon the wheel may be brought up to the work to face grind it by hand actuation of the feed lever 35.

However, in order that the proper facing position may be accurately determined, and this notwithstanding wheel wear and truing of the face grinding face, provision may be had for locking the wheel carriage in the proper axial positions, both for face grinding and for face truing of the grinding wheel. For this purpose mechanism shown best in Figures 3, 4 and 6 to 8 may be employed. In the frame of the machine there is axially movably mounted a threaded bar 210. One end of this bar is threaded into a sleeve 211 (see Figure 8) which is journaled through a fixed bracket portion 212 and has secured to its outer end a retaining collar 213. This sleeve 211 is thus rockably mounted but is held against axial motion. Its outer end is provided with an actuating handle lever 214 by which it may be turned, and the amount of turning may be shown by index markings on the head portion 215 of the sleeve 211 in connection with a reference point 216 marked on the bracket portion 212. This bar 210 is keyed against turning motion, being provided with a key 220 engaging in a keyway 221 in a bearing portion 222 spaced from the bracket portion 212, and a spring 223 seated in an end socket therein and bearing against a cap plate 224 presses the element 210 axially to take up lost motion in its threaded connection with the sleeve 211. This bar 210 has a longitudinal keyway 225 therein within which ride keys 226 of a pair of abutment collars 227 and 228, each of which is provided with an abutment portion 229 and 230. These

collars 227 and 228 may be adjusted axially of the bar 210 and secured in adjusted position by collars 232 threaded on the bar 210 and bearing against opposite faces of the collars 227 and 228. By adjustment of these collars 232, it is evident that the spacing between the abutment collars 227 and 228 may be adjusted as desired. The wheel carriage or slide is provided with a latch hook 240 (see Figure 4) having a hook recess 241 which may be engaged selectively on either of the abutments 229 or 230 and shown in dotted line in Figure 4 as engaging the abutment 229. When the latch hook 240 is in engagement with this abutment 229, the end face of the grinding wheel is adjusted to be in axial position to start face grinding of the work against which it may be fed by turning the hand lever 214 in the proper direction. When the latch hook 240 is in engagement with the abutment 230, the grinding end face of the wheel is removed from face grinding position and retracted to a point where it is in position to be face trued. A truing device 245 mounted on the work carriage may be employed for this purpose. This truing device is shown in Figures 3 and 9. It comprises a diamond holder 250 adjustable axially in a sleeve 251, this sleeve being pivoted at 252 on a support 253. It may be rocked downwardly into the position shown in Figure 9 when the work carriage 2 is in grinding position, whereupon a diamond truing tool 254 is in position to dress the periphery of the wheel, but in moving the truing device to this position, a second truing device 255 carried by an arm 256 secured to the holder 250 sweeps across the end face of the wheel as shown by the double arrow in Figure 9. It will be noted that this truing device 255 is positioned a fixed distance from the work carriage in the direction of motion of the wheel carriage, so that the abutment 230 may be adjusted to bring the wheel face away from the work face to exact relation to the truing device. Thus when the wheel carriage is retracted, and its latch hook 240 is engaged with the abutment 230, it is in position for the truing device to be brought down to true its end face. As, however, this truing of the end face and also the wheel wear, removes the material of the wheel, the latch may be moved along the wheel carriage to move the wheel carriage toward the work carriage to compensate for this as will later appear.

When the latch 240 is in engagement with either of the abutments 229 or 230, this carriage should be disconnected from the power traverse. Means are provided, therefore, for preventing the latch 62 from engaging the power traverse lever 60 when the latch hook 240 engages either of the stops 229 or 230. To this end, the latch 62 is provided at its end remote from the hook 65 with an upwardly extending arm 260 and the latch 240 is provided with a similar upstanding portion 261. These are arranged to project above a table portion 262 which carries the pivot 63 for the hook 62 and the pivot 263 for the hook 240, and in line with these hooks are axially movable bars 266 and 267. As best shown in Figure 8, these bars 266 and 267 are adapted to engage a cam member 270 carried by a vertical shaft 271 provided with an actuating handle 272 at its upper end. The cam member 270 is so formed that only one of the bars 266 and 267 can be in an axial position at one time permitting the corresponding hook to be in depressed position, the rocking of the handle 272 from one angular position to another acting to raise one

hook and allowing the other to descend. In intermediate position, both of these hooks are in raised position and out of engagement with their respective cooperating members. In this intermediate portion of the handle 272, the wheel carriage can be moved axially freely by manipulation of the handle 36. The table 262 which supports these hooks may be adjusted in line of motion of the wheel carriage with respect thereto, and for this purpose it is shown, as shown best in Figure 7, as consisting of a slide having a dovetail foot 273 fitted between ways, one of which at 276 is adjustable, the slide 275 engaging a lead screw 280 connected through intermeshing spiral gears 281 and 282 (see Figure 8) with an adjusting shaft 283 provided on the outer face of the carriage 3 with a hand wheel 289. This adjustment compensates for grinding wear and truing for the wheel face without changing the relation of the abutments 229 and 230, the handle lever 214 and the graduations 216, the diamond holder, and the face of the work.

In setting up for face grinding, the diamond point 255 is set at some known distance from the finished face of the work. The lugs 229 and 230 are then spaced on the threaded bar 210 so that the distance between them is equal to the distance from the diamond point to the finished face of the work minus a safe allowance for stock which is to be removed from the work, the lug 230 being adjusted first so that the face of the grinding wheel just contacts the diamond point when the lug 230 is engaged by the latch 240 and the lever 214 is at its rear position, preferably engaging a stop 2140.

With the latch 240 engaging the lug 230, the diamond 255 is then brought across the face of the grinding wheel, and the wheel is fed into the diamond by turning the knob 289. The face of the wheel having been dressed, the diamond holder is swung clear of the wheel and the latch 240 is transferred to the lug 229. This will bring the face of the grinding wheel close to the rough face of a work piece. By swinging the lever 214 forward, the wheel carriage is moved to the left at a feeding rate under control of the lever 214. A positive stop 2141 is provided to limit the amount of axial feed by motion of lever 214, or, if preferred, the graduations 216 may be used to determine when the proper amount of stock has been removed. By following this method, the face of the work piece will be held in proper relation with other faces or locating points of the work regardless of wear of the grinding wheel, which is compensated for automatically as the knob 289 is turned, and the face of the wheel is dressed off in fixed relation to the finished surface of the work.

When the same wheel is used for both hole and face grinding, the cylindrical surface of the wheel is shortened as the face wears back. This means that the left hand edge of the wheel does not reach as deeply through the hole, and in the case of a blind hole may mean that the whole depth will not be ground unless the stroke is changed to keep up with this wear. This correction is accomplished automatically on this machine since the wheel latch 62, which is used for the hole grinding traversing stroke, is mounted on the pivot pin 263 which is moved to compensate for wheel face wear, the position of the grinding stroke being altered simultaneously with the compensation for wheel face wear when the knob 289 is turned while dressing the face of the wheel.

11

From the foregoing description of an embodiment of this invention, it should be evident to those skilled in the art that various changes and modifications might be made without departing from its spirit or scope.

We claim:

1. In combination, a support, a pair of carriages on said support mounted for relative rectilinear motions at substantially right angles to each other, one of said carriages supporting a tool and the other of said carriages supporting work to be operated upon by said tool, means for moving said tool carriage through a path of predetermined length to effect a traverse of said tool relative to the work and to extend such motion at predetermined times to retract the tool from the work in traverse direction, and means actuated automatically when said tool carriage reaches a predetermined retracted position with said tool clear of the work to move said work carriage in its linear direction away from a normal tooling position to another position.

2. In combination, a support, a pair of carriages on said support mounted for relative sliding motions at substantially right angles to each other, one of said carriages supporting a tool and the other of said carriages supporting work to be operated upon by said tool, means for moving said tool carriage through a path of predetermined length to effect a traverse of said tool relative to the work and to extend such motion at predetermined times to retract the tool from the work in traverse direction, and means actuated automatically when said tool carriage reaches a predetermined retracted position with said tool clear of the work to move said work carriage in its linear direction away from a normal tooling position to another position and for returning said work carriage to normal tooling position as said tool carriage is being returned from extended to normal tooling traverse.

3. In combination, a support, a pair of carriages on said support mounted for relative sliding motions at substantially right angles to each other, one of said carriages supporting a tool and the other of said carriages supporting work to be operated upon by said tool, means for moving said tool carriage through a path of predetermined length to effect a traverse of said tool relative to the work and to extend such motion at predetermined times to retract the tool from the work, means actuated automatically when said tool carriage reaches a predetermined retracted position to move said work carriage away from a normal tooling position to another position and for returning said work carriage to normal tooling position as said tool carriage is being returned from extended to normal tooling traverse, said automatically actuated means including a crank arranged to approach a dead center position as said work carriage approaches normal tooling position.

4. In combination, a support, a pair of carriages on said support mounted for relative sliding motions at substantially right angles to each other, one of said carriages supporting a tool and the other of said carriages supporting work to be operated upon by said tool, means for moving said tool carriage through a path of predetermined length to effect a traverse of said tool relative to the work and to extend such motion at predetermined times to retract the tool from the work in traverse direction, and means actuated automatically when said tool carriage reaches a predetermined retracted posi-

12

tion with said tool clear of the work to move said work carriage in its linear direction away from a normal tooling position to another position and for returning said work carriage to normal tooling position as said tool carriage is being returned from extended to normal tooling traverse, said automatically actuated means including mechanism slowing down the motion of said work carriage as it approaches either of its said positions.

5. In combination, a support, a carriage mounted for motion on said support, a feed screw, a nut journaled on said support and through which said screw is threaded, an abutment on said carriage normally contacting one end of said feed screw, means for rotating said nut to move said screw axially and thereby feed said carriage, and mechanism engaging said screw and carriage and operative to move said carriage relative to said screw in a direction to retract said abutment from said screw to a predetermined distance and to return said carriage to bring said abutment against said screw.

6. In combination, a support, a carriage mounted for motion on said support, a feed screw, a nut journaled on said support and through which said screw is threaded, an abutment on said carriage normally contacting one end of said feed screw, means for rotating said nut to move said screw axially and thereby feed said carriage, and mechanism engaging said screw and carriage and operative to move said carriage relative to said screw in a direction to retract said abutment from said screw to a predetermined distance and to return said carriage to bring said abutment against said screw, said mechanism comprising a crank and link disposed in substantially dead center relation when said carriage is in either of its two positions.

7. In combination, a support, a carriage mounted on said support for motion in a rectilinear path, a member mounted for motion substantially in said path, power means for moving said member alternately in opposite directions, a releasable latch for connecting said member and carriage, a member adjustable lengthwise of said path, a releasable latch for connecting said adjustable member and carriage to lock said carriage in adjusted position, and means operative to release one of said latches when the other of said latches is to be made operable.

8. In combination, a work holder, a grinding wheel holder, means for relatively moving said holders in one manner to cause said wheel to face grind work carried by said work holder, and in another manner to cause said wheel to traverse the work, means for truing the end face of said wheel for face grinding, means for limiting the traverse in the direction of approach of said end face, and means for automatically adjusting said traverse limit in accordance with the decreasing length of the face wheel as said end face is trued to cause said end face to reach the same limit of traverse on the work during the relative traversing motion of said holders regardless of such truing.

9. In combination, a support, a carriage mounted on said support for motion in a rectilinear path, a face grinding wheel mounted for rotation on said carriage, a work holder toward and from which said carriage moves, a grinding wheel face truing device spaced from work on said work support in the direction of motion of said carriage and movable transversely of said direction to face dress said wheel when said wheel is spaced

a predetermined distance from the face of the work, an element mounted on said support parallel to said carriage motion, stops adjustably spaced on said element one corresponding to the position of the work face and the other corresponding to the position of said truing device, means to lock said carriage to either selected of said stops to locate said wheel in face grinding or truing positions depending upon the stop to which said carriage is locked, and means for adjusting the endwise positions of both stops simultaneously.

10. In combination, a support, a carriage mounted on said support for motion in a rectilinear path, a face grinding wheel mounted for rotation on said carriage, a work holder toward and from which said carriage moves, a grinding wheel face-truing device spaced from work on said work support in the direction of motion of said carriage and movable transversely of said direction to face dress said wheel when said wheel is spaced a predetermined distance from the face of the work, an externally threaded element mounted on said support parallel to said carriage motion, stops keyed to said element, collars threaded on said element on each side of said stops for adjusting and locking said stops in axially spaced relation corresponding to the position of the work face and to the position of said truing device, respectively, means for locking said carriage to either selected of said stops to locate said wheel in face grinding or truing positions, respectively, and means for adjusting said element axially to thereby feed said wheel into the face of the work.

11. In combination, a support, a carriage mounted on said support for motion in a rectilinear path, a face grinding wheel mounted for rotation on said carriage, a work holder toward and from which said carriage moves, a grinding wheel face-truing device spaced from work on said work support in the direction of motion of said carriage and movable transversely of said direction to face dress said wheel when said wheel is spaced a predetermined distance from the face of the work, an externally threaded element mounted on said support parallel to said carriage motion, stops keyed to said element, collars threaded on said element on each side of said stops for adjusting and locking said stops in axially spaced relation corresponding to the position of the work face and to the position of said truing device, respectively, means for locking said carriage to either selected of said stops to locate said wheel in face grinding or truing positions, respectively, means for adjusting said element axially to thereby feed said wheel into the face of the work, and means for adjusting said locking means on said carriage lengthwise of said carriage motion to compensate for wheel face wear and truing.

12. In combination, a support, a pair of carriages on said support mounted for relative sliding motion at substantially right angles to each other, one of said carriages supporting a tool and the other of said carriages supporting work to be operated upon by said tool, means for moving said tool carriage through a path of predetermined length to effect a traverse of said tool relative to the work and to extend such motion at predetermined times to retract the tool from the work, means actuated automatically when said tool carriage reaches a predetermined retracted position to move said work carriage away from a normal tooling position to another position, and

means for locking said work carriage in a position intermediate to its normal and said other positions.

13. In combination, a support, a pair of carriages on said support mounted for relative sliding motions at substantially right angles to each other, one of said carriages supporting a tool and the other of said carriages supporting work to be operated upon by said tool, means for moving said tool carriage to effect a traverse of said tool relative to the work, a crank journaled on said work carriage perpendicular to its sliding direction, a link pivoted at one end on said crank, an anchor member to which the other end of said link is pivoted, said member and crank journal being spaced in the sliding direction of said work support, and means for rocking said crank to thereby move said work support.

14. In combination, a support, a pair of carriages on said support mounted for relative sliding motions at substantially right angles to each other, one of said carriages supporting a tool and the other of said carriages supporting work to be operated upon by said tool, means for moving said tool carriage to effect a traverse of said tool relative to the work, a crank journaled on said work carriage perpendicular to its sliding direction, a link pivoted at one end on said crank, an anchor member to which the other end of said link is pivoted, said member and crank journal being spaced in the sliding direction of said work support, means for rocking said crank from one to another angular position to move said work support between an operative and inoperative position, and a work feed mechanism connected to said anchor member for moving said anchor member in the direction of motion of said work support.

15. In combination, a support, a pair of carriages on said support mounted for relative sliding motions at substantially right angles to each other, one of said carriages supporting a tool and the other of said carriages supporting work to be operated upon by said tool, means for moving said tool carriage to effect a traverse of said tool relative to the work, a crank journaled on said work carriage perpendicular to its sliding direction, a link pivoted at one end on said crank, an anchor member to which the other end of said link is pivoted, said member and crank journal being spaced in the sliding direction of said work support, means for rocking said crank from one to another angular position to move said work support between an operative and inoperative position, a feed screw carrying said anchor member, a feed nut engaging said screw and journaled in said support, and means for turning said nut.

16. In combination, a support, a pair of carriages on said support mounted for relative sliding motions at substantially right angles to each other, one of said carriages supporting a tool and the other of said carriages supporting work to be operated upon by said tool, means for moving said tool carriage to effect a traverse of said tool relative to the work, a crank journaled on said work carriage perpendicular to its sliding direction, a link pivoted at one end on said crank, an anchor member to which the other end of said link is pivoted, said member and crank journal being spaced in the sliding direction of said work support, means for rocking said crank from one to another angular position to move said work support between an operative and inoperative position, a feed screw carrying said anchor member, a feed nut engaging said screw

and journaled in said support, and means for turning said nut, said carriage having an abutment alined with said feed screw and engaging the outer end of said feed screw at one limit of motion of said carriage as produced by rocking of said crank.

17. In combination, a support, a pair of carriages on said support mounted for relative sliding motions at substantially right angles to each other, one of said carriages supporting a tool and the other of said carriages supporting work to be operated upon by said tool, means for moving said tool carriage to effect a traverse of said tool relative to the work, a crank journaled on said work carriage perpendicular to its sliding direction, a link pivoted at one end on said crank, an anchor member to which the other end of said link is pivoted, said member and crank journal being spaced in the sliding direction of said work support, means for rocking said crank from one to another angular position to move said work support between an operative and inoperative position, a feed screw carrying said anchor member, a feed nut engaging said screw and journaled in said support, means for turning said nut, a pair of alined abutments one on said carriage and the other on said support, and a stop member interposable between said abutments to hold said carriage in a position intermediate to said operative and inoperative positions.

18. In combination, a support, a pair of carriages on said support mounted for relative sliding motions at substantially right angles to each other, one of said carriages supporting a tool and the other of said carriages supporting work to be operated upon by said tool, means for moving said tool carriage to effect a traverse of said tool relative to the work, a crank journaled on said work carriage perpendicular to its sliding direction, a link pivoted at one end on said crank, an anchor member to which the other end of said link is pivoted, said member and crank journal being spaced in the sliding direction of said work support, means for rocking said crank from one to another angular position to move said work support between an operative and inoperative position, a feed screw carrying said anchor member, a feed nut engaging said screw and journaled on said support, means for turning said nut, a pair of alined abutments one on said carriage and the other on said support, a stop member interposable between said abutments to hold said carriage in a position intermediate to said operative and inoperative positions, and a micrometric adjustment means for adjusting one of said abutments toward and from the other of said abutments.

19. A grinding machine having a pair of supports, means mounting one of said supports for motion from and toward the other of said supports, a work carrier on one of said supports, a grinding wheel carried by the other of said supports for operating on the work, means for moving the movable support including a rotary crank and a link operatively connecting said crank to said movable support, and means for adjusting the throw of said crank to adjust the amplitude of stroke of said movable support, the effective length of said link being adjustable to adjust the positions of said movable support at the limiting end portions of said stroke.

20. In combination, a support, a pair of carriages on said support mounted for relative recti-

linear motion at substantially right angles to each other, one of said carriages supporting a tool and the other of said carriages supporting work to be operated upon by said tool, means for moving said tool carriage through a path of predetermined length to effect a traverse of said tool relative to the work and to extend such motion at predetermined times to retract the tool from the work in traverse direction, and means actuated automatically when said tool carriage reaches a predetermined retracted position with said tool clear of the work to move said work carriage in one direction away from a normal tooling position to another position and for returning said work carriage in the opposite direction to normal tooling position as said tool carriage is being returned from said extended to normal tooling traverse.

21. In combination, a support, a pair of carriages on said support mounted for relative rectilinear motion at substantially right angles to each other one forwardly and rearwardly and the other laterally, a tool supported by said laterally movable carriage, a work holder supported by said forwardly and rearwardly movable carriage, means for moving said tool carriage through a path of predetermined length to effect traverse of the tool relative to work on said work holder and to extend such motion at times to retract the tool from the work in traverse direction, and means actuated automatically when the tool carriage reaches a predetermined retracted position with said tool clear of the work to move said work carriage forwardly from a normal tooling position to facilitate access to the work.

22. In combination, a support, a pair of carriages on said support mounted for relative rectilinear motion at substantially right angles to each other one forwardly and rearwardly and the other laterally, a tool supported by said laterally movable carriage, a work holder supported by said forwardly and rearwardly movable carriage, means for moving said tool carriage through a path of predetermined length to effect traverse of the tool relative to work on said work holder and to extend such motion at times to retract the tool from the work in traverse direction, and means actuated automatically when the tool carriage reaches a predetermined retracted position with said tool clear of the work to move said work carriage forwardly from a normal tooling position to facilitate access to the work and to return said work carriage to normal position as said tool carriage is being returned from extended to normal tooling traverse.
